SHIP HULL CONSTRUCTION

Gustav Meier, West New Brighton, N. Y.

Refiled for application Serial No. 499,776, August 24, 1943. This application July 9, 1946, Serial No. 682,353

2 Claims. (Cl. 114—79)

1

The present application is a re-filing of application Ser. No. 499,776, filed Aug. 24, 1943, and which has since become abandoned.

This invention relates to new and useful improvements in the construction of ship hulls, and more especially for high speed ship hulls.

Thus one of the main objects of my invention is to obtain reduction of the water resistance to a ship hull, and thereby increase the speed of the ship.

Another object is to eliminate stresses in the hull and to obtain stiffness in the construction of the latter.

A further object of my invention is to provide a transverse welding of the plates arranged between the conventional webframes.

A yet further object of my invention is to provide substantially rectangularly shaped hull sections which decrease in height rearwardly, and thus provide said hull with step-formed off-sets rearwardly, preferably from midships to the stern of the ship, giving the bottom of said individual off-sets a straight horizontal surface.

Through this construction it is possible to save cost in the building of ships, as each section, that is plates with the attached webframes may be prefabricated, so as to be readily assembled into a complete hull when these sections are welded together, whereby a uniform contraction during welding is attained, thus eliminating locked up stresses.

By this construction, as set forth, it has been estimated that a considerable cost of labor will be saved while an increased speed of the ship is attained.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is a side elevational view of a ship, illustrating my invention.

Figure 2 is a horizontal, longitudinal view partly in section, taken on the line 2—2 in Figure 1.

Figure 3 is a fragmentary vertical, longitudinal section, taken on the line 3—3 in Figure 2, showing my invention in detail.

Figure 4 is a fragmentary vertical, longitudinal section, taken on the line 4—4 in Figure 3.

Figure 5 is a transverse vertical section, taken on the line 5—5 in Figure 1.

My invention relates to ship hull construction, particularly to hulls having sections which decrease in height rearwardly, and which are joined together by means of webframes, the hull being formed with substantially horizontal bottom, the rear of said hull from about midships being formed with step-like off-sets, the latter decreasing in height towards the stern.

Figure 6 is an enlarged detail sectional view, showing the joining of two sections with a web-frame.

Figure 7 is a detail sectional view of Figure 6, looking in the direction of the arrow.

Referring more particularly to the drawing, the numeral 10 indicates a ship hull having a reduced underwater portion 11 extending approximately from midships to the stern.

10 The said underwater portion comprises a plurality of sections 12 joined together by means of webframes 13.

Shell plates 14 are welded transversely to the said frames 13, as indicated at 15 and 16.

15 While the front of the hull is formed with a substantially horizontal bottom, the rear of said hull from about midships is formed with step-like off-sets; the latter decreasing in height towards the stern.

20 The said hull sections with webframes, which may be pre-fabricated, are connected by members 18, the latter having a length equal to distance between two webframes.

25 While the members 18 of the forward portion of the hull are flush with the webframes, the members 18 at the rear portion of the hull are at the bottom arranged in such a manner as to form step-like off-sets 17.

30 Thus in welding said members 18 together at the rear bottom portion, each member is in rearward succession welded to the webframe in front thereof (that is, in direction of the stem); said members 18 forming right angles with the webframes.

35 While the shell plates on the sides of the hull and bottom from midships to the stern of the hull are flush and forming seams 19, the shell plates at the rearward portion of the hull from midships, are forming step-like off-sets conforming to the position of the members 18, and are welded to the webframes as at 20 and 21.

40 Reinforced plates 22 and 23 are arranged between the members 18 and webframes 13.

The keel 24, while slanting rearwardly, is se-

45 cured at the bottom of the webframes and rearward ends of the members 18.

50 Substantially triangular plates 25, conforming to the spaces formed between the bottom shell plates, the step-like off-sets and the keel, are welded to the shell plates 14 as at 26, and the keel 24, as shown at 27.

55 It is obvious that changes may be made in the

form, construction and arrangement of the several parts, as shown, within the scope of the ap-

55 pended claims, without departing from the spirit

of the invention, and I do not, therefore, wish to limit myself to the exact construction shown and described herein.

What I claim as new, and desire to secure by Letters Patent of the United States, is:

1. A ship hull as described, including a plurality of webframes successively aligned and equally distanced and extending transversely across the hull, members welded to said webframes at right angles to the latter, said webframes off-set successively longitudinally of the hull from about amidships to the stern thereby forming step-like off-sets from about midships to the stern, and shell plates welded to said webframes across the hull to form sections, a keel underneath said hull and slanting upwardly toward the stern from approximately midships of the hull, said slanting portion of the keel being secured to one end only of each of the hull sections.

2. In an invention, as claimed in claim 1, and

wherein the shell plates, the step-like off-sets and the keel form triangular spaces, and plates conforming in shape to said spaces being welded into the latter.

GUSTAV MEIER.
